CLOTHES HANGER

Ivan L. Austensen, Battle Creek, Mich.

Application January 7, 1949, Serial No. 106

Term of patent 7 years

(Cl. D80—8)

To all whom it may concern:

Be it known that I, Ivan L. Austensen, a citizen of the United States, residing at 1000 Capital Avenue, S. W., Battle Creek, in the county of Calhoun and State of Michigan, have invented a new, original, and ornamental Design for a Clothes Hanger, of which the following is a specification, reference being had to the accompanying drawing, forming a part thereof.

Fig. 1 is a perspective view of my new design of clothes hanger;

Fig. 2 is a bottom plan view of the hanger shown by Fig. 1; and

Fig. 3 is a top plan view of the hanger shown by Fig. 1.

I claim:

The ornamental design for a clothes hanger, as shown.

IVAN L. AUSTENSEN.
